US00D884866S

(12) **United States Design Patent** (10) **Patent No.:** **US D884,866 S**
(45) **Date of Patent:** **** May 19, 2020**

(54) **FILTER ELEMENT**

(71) Applicant: **Cummins Filtration IP, Inc.**,
Columbus, IN (US)

(72) Inventors: **Jessie A. Knight**, Oregon, WI (US);
Scott G. Manke, Sun Prairie, WI (US)

(73) Assignee: **CUMMINS FILTRATION IP, INC.**,
Columbus, IN (US)

(**) Term: **15 Years**

(21) Appl. No.: **29/646,936**

(22) Filed: **May 8, 2018**

(51) LOC (12) Cl. **23-04**

(52) U.S. Cl.

USPC **D23/365**

(58) **Field of Classification Search**

USPC D23/209, 235, 341, 358, 363-365, 393;

D15/5; 210/355; 55/498

CPC F02M 35/04; F02M 35/10; F02M 35/024;

B01D 46/0002; B01D 46/10

CLAIM

We claim the ornamental design for a filter element, as shown and described.

DESCRIPTION

FIG. 1 is a bottom perspective view of the claimed design; FIG. 2 is a top perspective view thereof; FIG. 3 is a bottom plan view thereof; FIG. 4 is a top plan view thereof; FIG. 5 is a front elevation view thereof; FIG. 6 is a rear elevation view thereof; FIG. 7 is a left side elevation view thereof; and, FIG. 8 is a right side elevation view thereof. The broken lines formed by dashes show unclaimed subject matter and form no part of the claimed design.

1 Claim, 7 Drawing Sheets
